OVERHEAD LIGHTING SYSTEM FOR
MINIATURE THEATERS

Albert R. Johnson, New York, N. Y.

Application March 31, 1952, Serial No. 279,501

3 Claims. (Cl. 240—1)

1. The present invention relates to a miniature theatre and it particularly relates to a lighting arrangement particularly to be utilized in connection with a miniature theatre to give unusual, controlled lighting effects.

It is among the objects of the present invention to provide a novel miniature theatre, and particularly a lighting arrangement therefor, which will enable complete presentation of dramatic productions and give not only a complete lighting arrangement and variation of lighting effects as is possible in the commercial theatre but in addition to give unusual, attractive lighting effects particularly designed for a miniature theatre and to give greater emphasis in view of the smaller size.

A further object of the present invention is to provide a miniature theatre and particularly an illuminating arrangement therefor which will enable accurate adjustment and control of the illumination, including spot lighting, color changes and gradations in the lighting values as will best expose the curtain or stage to view or to enable emphasis to be placed upon different parts of the stage or upon the characters being displayed or dramatized thereon.

Another object of the present invention is to provide a small, miniature stage which may be readily operated for constructional as well as professional purposes, which may be widely employed in a school as well as in dramatic meetings or societies and which can be employed to demonstrate various theatrical presentations at low cost and without the necessity of exceptional training on the part of the workmen or employees.

Another object of the present invention is to provide a simple, durable, readily collapsed and re-assembled miniature theatre construction which is substantially fire-proof and without electrical switches or other spark-causing devices, and with even one or two electric bulbs, to give a wide variety, range and control of color, gradation, spot lighting and so forth.

Still further objects and advantages will appear in the more detailed description set forth below; it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory to form the entire stage

of a series of slotted, heavy paper or plastic sheets, so arranged that they may be connected to one another as the front, back, floor, ceiling and cover of a miniature theatre.

5. In the preferred embodiment, the material which is employed is of fire-proof material or of material which is treated so as to be fire-proof, and above the theatre and between the roof and ceiling or dome is positioned a single or several electric bulbs, a single bulb usually being preferable, which will serve as the sole source of illumination.

The present invention is particularly directed to the manner in which this single bulb, or several bulbs, is transmitted to or arranged upon the stage.

20. The ceiling or roof at the top of the stage, consisting of a horizontal, plastic or treated paper sheet, is desirably provided with a series of passageways or parallel arrangements positioned closely side by side and extend from side-to-side laterally of the miniature theatre.

25. Each of these passageways is provided with a hinged shutter arrangement, preferably hinged at the rear of each passageway or parallel arrangement and designed to be elevated toward the light or moved downwardly away from the light, so as to give a controlled illumination to different portions of the stage from the front to the back thereof.

Desirably, these shutters may be made by having a sheet of paper or plastic material with top and bottom cover faces which extend over or are attached to the upper face or top face of the roof of the theatre and which will serve as hinge or pivot connections.

In addition, each passageway or light runway, at the top of the roof is provided with adjustable slide members which may vary the color or the distribution of the light apart from and independent of the shutters.

For example, the slide members may have a series of transverse or longitudinal slots or circular or oval openings arranged at such position that as they are moved or slid along the passageways, they will either change the coloration of the light or cause concentration of the light or spot-light of different portions of the sections of the stage from front to back thereof.

Desirably, the acting figures may be provided with faces which may be of permanent magnet material, such as the alloy known as "Alnico" and below the floor of the theatre there may be positioned slider members with magnets thereon.

to move these figures around in predetermined position.

The magnets on the control members below the stage, as well as at the base of the figures, are desirably so arranged that by suitable manipulation, the figure can be caused to turn or can be caused to face forwardly at all times, and if desired will not at any time turn its back upon the audience.

In the preferred construction, the dome of the theatre is provided with suitable ventilation to ventilate the heat of the illuminating electric bulb, and similarly the front of the theatre is provided with a pull-up or drop-down curtain which may be co-ordinated with a lighting arrangement at the front or the top section of the stage to give a simulated lighting for the theatre when the curtain is down, which lighting is automatically cut off when the curtain is lifted.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Fig. 1 is a front elevational view of the stage, showing the top lighting arrangement with the curtain elevated and with several of the figures in position.

Fig. 2 is a side elevational view upon the line 2—2 of Fig. 1.

Fig. 3 is a transverse central vertical sectional view upon the line 3—3 of Fig. 1.

Fig. 4 is a horizontal sectional view upon the line 4—4 of Figs. 1, 2 and 3.

Fig. 5 is a horizontal sectional view upon the line 5—5 of Figs. 1, 2, and 3.

Fig. 6 is a top perspective view of a color slide which may be utilized in controlling the color of the light from the top of the theatre.

Fig. 7 is a top perspective view showing a slideable spot-light control arrangement.

Fig. 8 is a top perspective view of a magnet control bar for controlling the movement and position of the figures to be inserted through and utilized under the floor of the stage.

Fig. 9 is a rear perspective view of a typical figure which may be utilized for producing the theatrical or dramatic performance.

Referring to Figs. 1 to 4, the arrangement has a stage A with a floor structure B and a lighting dome C.

The present invention is particularly directed to the lighting or illuminating control system D, which embodies the hinged shutters E, F, G and H and the slideways or runways J, K, L and M.

Cooperating with the control shutters E, F, G and H on the runways J, K, L and M are the color slides N and the control spot-light illumination slides O.

The stage itself is provided with a series of partition members P which may give back-drop effects or serve to give partial or complete back scenery, and on the floor B of the stage A are positioned the figures R shown in small scale in Figs. 1, 2 and 3 and in large scale in Fig. 9.

Below the floor of the theatre may be positioned the control bars S which will control and enable adjustment of the figures R.

The theatre structure itself is preferably provided with interfitting flats of sheet material, such as fiberboard, cardboard, plywood, plastic or even light metal, and the members may be connected to one another by slotted connections, screws, pins or dowels.

There is provided a front, vertical main sheet element 10 to which is connected the rearwardly extending face member 11, the rearwardly extending floor stage member 12 and the floor roof member 13.

The dome C is formed of the top element 14, the downwardly extending front member 15, the rearwardly and downwardly extending member 16, and there may be a back cover member 17 closing off the rear of the theatre.

Mounted in the ceiling 44 is the socket 25 having the flange connection 26 which received the light bulb 27.

The sides 28 of the dome C are desirably provided with the ventilating arrangement 29 to permit flow of air through the dome C.

The light from the bulb will normally pass forwardly to the front lighting arrangement 30 in the front, vertical member 10, as indicated by the arrow 31, and it will also pass downwardly as indicated by the arrows 33, 34, and 35, into each of the runways J, K, L and M in an amount depending upon the position of the shutters E, F, G and H.

To the rear of the front member 10 is the curtain 36, which may be engaged between the front member 10 and the rear panel 37. This curtain when drawn up to the position of the openings 30 will cut off the light from the bulb 27, passing in the direction 31.

The curtain 36 may be raised and lowered by the cord 38, which passes over the guides 39 and 40 and may be tied at 41 on the rear of the panel 10 and to the side of the stage A.

As is shown best in Fig. 3 the ceiling or roof 13 of the stage A has a plurality of grooved members 50, 51, 52, 53 and 54 which form runways or slotways for insertion of the elements N and O and which are positioned below the shutters E, F and G.

At the sides of the miniature theatre, as shown in Fig. 2, there are provided slots 55, 56, 57 and 58 which communicate with the slideways formed by the grooves in the blocks 50, 51, 52, 53 and 54.

It is possible to insert in the slots 55 to 58 and in the grooves of the blocks 50 to 54 the color slides N as well as the spot-light slides O, to give a controlled distribution of color and spot-light illumination to the front and back of the stage.

As shown in Fig. 6, the color slide is relatively stiff so it may be slid in and out of the slots 55 to 58 and it may all be of one color or of a gradation of different colors from side to side or from end to end.

The slider O, on the other hand, is shown with one opening 59 but there may be a whole series of different size and shape openings in different rows or other arrangements, as for example as indicated by the circular opening 60 and the relatively rectangular opening 61 of Fig. 4.

By positioning these openings at different places along the slideways J to M, the light on the stage may be adequately controlled.

In the spot-light slider O, it will be noted that there is a stop shoulder or head 62 with the projecting edges 63, which will enable convenient gripping of the end of the slider O.

The transparent elements desirably have similar beads 64 with the shoulders 65, which may

be manipulated from the opposite ends of the runways J to M.

As shown in Fig. 3, the shutters E to H all face toward the light in an upright position and they desirably are provided with reflecting faces at 66, 67, 68 and 69 to reflect the light downwardly on the stage A. Their hinges 70, 71, 72 and 73 may be mounted on the blocks 50, 51, 52 and 54 and they may consist of a surface ply which is pasted to both the shutters E to H as well as the mounting blocks.

These shutters are slotted so as to be guided along the quarter circular edges 74, 75, 76 and 77 in the side panel members 28, and there is a sufficient projection, as indicated at 78, 79, 80 and 81, to give a handle which enables suitable adjustment of the angular position.

In the arrangement shown in Figs. 2 and 3, each of the shutters E to H are in vertical position, giving the maximum illumination to the stage A from the light 21. This may be varied by lowering the shutters E to H where they will close off entirely the runways or slot-ways J to M to cut off all light upon the stage A.

In Fig. 4 the runway or slot-way L is shown empty, without either spot-light or color slides in position and with the entire area of the slot defined by the end edges 90 and the side edges 91 being available for passage of light from the light source 27.

This will give a maximum illumination to the portion of the stage, indicated by the numeral 92 in Figs. 2 and 3, below the slot-way or runway L.

The rear slot-way or runway M is provided with a color slide N which will illuminate the portion of the stage indicated by the numeral 93 with the color of the particular slide N.

In the slot-way or runway K, there is both a stop light at 61 as well as the color slide N, giving a colored spot upon the figure R at position 94 in Figs. 2 and 3. The front slot-way or runway J will also have a spot-light of smaller dimension below 60, which will be covered by the color slide N.

By arranging the position of the shutters E, H and the position of the color slide N and the spot-light slides O, the illumination on the stage may be controlled in accordance with the requirements of the dramatic situation and the position of the figures R.

Referring to Figs. 2 and 3, it will be noted that there are a series of slide member P in position to give the back-drop or scenery effect.

Depending from the ceiling 13 may be a series of members 100 to 106 which form the slots 107, 108, 109, 110, 111, 112 and 113. These slots co-operate with the slot members 114, 115, 116, 117, 118, 119 and 120, which serve to hold the back-drop elements P in position both at the roof and floor of the state.

These scenes or back-drops may extend partly or wholly into the visible area of the stage to give the desired scenic effects.

It will be noted that the corners of the elements 100 to 106 are rounded, as indicated at 121, to enable more ready insertion of the back-drops or scenery effects P.

The figures as shown in Fig. 9 consist of upright simulations of the human form on a small scale, which are painted or decorated on their front sides, as shown in Fig. 1, and which are provided with bar magnets 131 with down-turned ends held in position by the clips 132.

Below the floor 12 of the state are a series of

guides or carriers 133, 134, 135, 136, 137 and 138, in which may be slid control members S with the end magnets 139.

Normally the figures R will be caused to move laterally across the stage rather than transversely back and forth between the slot-ways 107 to 113, and 114 to 120.

The polarity of the magnets 131 and 139 are so controlled as to give the desired effect and maintain the figures R passing forwardly at all times.

As shown in Fig. 5, a series of the control members S are indicated as being in position, controlling the figures R at the front and middle of the stage, with the magnets 139 positioned at one side of the stage.

However, these magnets may be readily moved to move the figures R laterally across the stage and in some instances the figures may be picked up by one magnet and moved to another magnet to give a back-and-forth motion as well as the lateral cross motion.

The front of the stage, as indicated at 145, has a series of foot-light arrangements which may be illuminated by a lamp positioned between the base 11 and the floor 12.

The aperture of the stage formed between the side edges 146, the top edge 147 and the bottom edge 148 may be widely varied in shape, design and expanse.

The apertures 90-94, as shown in Fig. 4, may be varied in number and size to control the illumination, and the hinges 70 to 73 of paper or cloth will be fairly durable and will not deteriorate with time.

It will be noted that the front shutters E, F and G close the rear shutter faces forwardly so that the front reflecting surface will always be directed toward the light source.

As indicated best in Fig. 5, the scenery or back-drops P are merely side elements and terminate at the side edges of the state, as indicated at 150, 151 and 152.

If desired, the stage floor 12 may have different levels instead of the same lever as indicated.

The color slides N may be either of transparent or translucent colored plastic sheet materials.

The grooves or recesses in the sides of the blocks 50 to 54 desirably are so wide that they can receive both the color slide N as well as the opaque spot-light slide O.

The theatre arrangement shown and designed for the presentation of plays, musical comedies, pageants, spectacles and pantomimes and there may be provided a complete working script and directions for each type of play or dramatic production.

The theatre may be operated by one or more persons and the entire miniature theatre is desirably positioned at eye level.

The operators may be positioned in back of a drop or screen of light, opaque material, which may be positioned alongside or back of the stage front 10.

The operators at the rear of the miniature theatre may have speaking parts and they will control the lighting shutters E to H and slides N, O and S.

The entire theatre as shown may be knocked down and packaged in small form and it may be assembled with or without the use of glue.

There may be a set of scenery or slides and figures R arranged for each type of dramatic or other production and a new play may be pro-

duced weekly or monthly, as the case may be, and it is particularly effective upon television.

The illumination 30 gives the effect of a chandelier of a theatre.

Although the structure is of miniature or toy size, it may be made much larger for actual trial dramatic productions.

While there has been described a preferred form of the invention, it should be understood that the same may be altered in details and in the relative arrangement of parts within the scope of the appended claims.

The present application is a continuation-in-part of application Ser. No. 728,877, filed February 15, 1947, and now abandoned.

Having now particularly described and ascertained the nature of the invention, and in what manner the same is to be performed, what is claimed is:

1. In a miniature or toy theatre of the type having a housing of light-weight sheet material having vertical front, back and side walls, a horizontal floor or deck forming a stage floor on which the action takes place, said front wall having an approximately rectangular opening through which the stage floor may be viewed from the front of the theatre, a top lighting structure including an open ceiling, a dome about said ceiling and an electric incandescent lamp positioned in said dome and positioned to shine 30 downwardly upon and illuminate the stage floor

through said ceiling, said ceiling having a plurality of transverse laterally extending apertures positioned in side-by-side relationship from the front to the back of the theatre, said transverse apertures permitting the light to illuminate the stage, and sliders movably inserted above said apertures to control the amount and color of said illumination and elongated rectangular reflectors pivotally mounted at the sides of the apertures to control the amount of light reflected through said apertures onto said stage.

2. The theatre of claim 1, said sliders including color light transmitting strips which will transmit the variation of the color across the stage from front to rear.

3. The theatre of claim 1 in which the sliders are opaque and have controlled openings to regulate the amount of light and position of light directed upon the stage from said top lighting structure.

ALBERT R. JOHNSON.
